UNITED STATES PATENT OFFICE.

SAMUEL O. HOFFMAN, OF SAN FRANCISCO, CALIFORNIA.

PRODUCTION OF LIGHT.

1,043,008.

Specification of Letters Patent. Patented Oct. 29, 1912.

Application filed July 17, 1911. Serial No. 638,911.

To all whom it may concern:

Be it known that I, SAMUEL O. HOFFMAN, citizen of the United States, residing in the city and county of San Francisco and State of California, have invented new and useful Improvements in Production of Light, of which the following is a specification.

This invention comprises a method for the production of light from an incandescent body, without the production of wasteful heat, and more generally, of producing radiation of particular wave lengths from a source emitting waves of the desired and other wave lengths, with a consumption of energy equivalent to the desired radiation only, and not to the total radiation of the source.

The drawings illustrate suitable means for practising the invention; Figure 1 being a side elevation in partial section of a complete lamp embracing the invention. Fig. 2 is a transverse section of a portion of the inner bulb of Fig. 1 drawn on a greatly enlarged scale. Fig. 3 is a modification, showing a simple form of the invention in which a film of silver is applied to the inner surface of a lamp bulb.

Light consists of waves in the ether of certain lengths, capable of affecting the retina. Waves of greater length, called infra-red waves are non-luminous. Both the luminous and infra-red waves upon absorption by a body are converted into heat. Aside from their physiological effects, the only difference between the luminous and infra-red waves is the longer wave length of the latter.

Practically all of the present systems of lighting depend upon the radiation of incandescent bodies. The radiation of such a body consists of waves of all lengths, only a small portion of which are luminous, most of the energy being in the longer non-luminous infra-red waves. The wave length carrying the maximum energy decreases as the temperature is raised, according to the Wien displacement law, and the higher the temperature the larger the proportion of luminous radiation present. At the highest possible operating temperature, only about 1%–5% of the radiation is of useful wavelength (luminous); the balance being infra-red waves and non-luminous, so-called heat waves. Thus at least 95% of the energy

used to keep the body incandescent is radiated as long non-luminous waves (heat) and so wasted.

My invention consists simply in separating the radiation of the incandescent body into the luminous and non-luminous portions, the small luminous percentage being allowed to radiate freely, while the non-luminous waves, representing most of the energy, are directed back to the incandescent body and used regeneratively, none being allowed to escape. Thus there is no loss of heat except that representing the small proportion of luminous radiation produced, and the energy required to keep the body at the necessary temperature is equivalent to the light produced, and not to the total radiation at that temperature, resulting in an enormous increase in efficiency.

Of course the simplest way of accomplishing this is to use a substance which transmits the luminous waves and reflects the non-luminous. I have found that a film of metallic silver, thin enough to be transparent, reflects a large proportion of the infra-red waves. Fig. 3 shows a lamp making use of this fact. A filament C is placed as nearly as possible along the axis of the cylindrical tube A, on the inside of which is deposited a thin film of silver. The lamp is otherwise similar to the ordinary incandescent electric lamp. The combined radiation from the filament strikes the inner metallic film normally, the infra-red waves are reflected back to the filament, while the light passes through. It is apparent that no energy can escape except in the form of light, and therefore, no wasteful heat is produced.

While I have only shown two methods of practising my invention, it is possible to make use of any means whatsoever by which the luminous waves can be separated from the non-luminous; the essence of my invention being the fact that the non-luminous radiation is directed back to the source without loss and used regeneratively. For instance with respect to the first method described, there are a large number of substances known to physicists which have the property of selective reflection. I have mentioned silver simply because I have actually and successfully tried it.

Another method of producing the inven-

tion is as follows: Instead of the film of silver, a glass bulb B shown in section in Fig. 2, is placed inside the tube A. This bulb has prismatic surfaces formed upon it, the effect of which is to transmit the light and reflect the infra-red waves. This bulb is made as thin as practicable, to prevent loss by absorption. Its action depends upon the following principles: A radiant beam passing obliquely from one medium to another is bent or refracted, to or from the normal to the oblique surface, depending upon whether the beam is entering a denser or rarer medium. The amount of refraction varies with the wave-length of the incident radiation, with the angle of incidence and with the nature of the medium. For any given medium and wave length, the ratio of the sines of the angles of incidence and refraction is a constant, known as the refractive index. For the same medium, the refractive index varies with the wave length of the incident radiation, being greater for luminous than infra-red waves, etc. If a radiant beam endeavors to pass from a dense to a rarer medium, at an angle to the normal greater than a certain critical angle, it will not succeed in passing out, but will be totally reflected; in fact this arrangement makes the most perfect reflector known. Now this critical angle of total reflection is equal to the angle whose sine is the reciprocal of the refractive index, and therefore, is less for waves of short than of long length and less for luminous than for infra-red waves. In a particular glass that I experimented with, the refractive index for red light, the light of longest wave length, was 1.528, and for the maximum infra-red 1.496. Therefore the critical angle for red light (sine of critical angle = reciprocal of refractive index) is $40^\circ 53'$, and for the maximum infra-red wave length about 43° . It is apparent therefore, that if a beam containing luminous and infra-red waves should seek to leave the glass at an angle to the normal of about 41° , the red and therefore all the luminous waves would be totally reflected, while the infra-red would pass out.

Referring to Fig. 2, which is a greatly enlarged section of a portion of the inner bulb B, the angles are as shown. Of course the necessary angles would depend upon the refractive index of the particular glass used, in this case the values are those given in the preceding paragraph. A radiant beam K from the filament containing luminous and infra-red waves enters the glass normally and strikes the surface M at an angle of 41° ; as this is greater than the critical angle for the luminous waves, they will be totally reflected along the path M P, again reflected at P and finally passing out normally H, but the angle 41° , is less than the critical

angle for the infra-red waves, therefore, they will pass out, being refracted along M O, striking the surface O of the right angle prism at an angle of 45° , and being reflected along O R, again reflected at R, along R S, entering the glass at S and passing out normally, T, thence back to the filament. It is thus seen that no radiant energy can escape from the filament except in the form of luminous waves, the infra-red waves, which carry more than 95% of the energy being continually reflected back, and used regeneratively. In the arrangement shown for practical reasons, there will be a small waste space as at E. To prevent loss, this space is closed with right angle prisms which reflect back both light and infra-red radiation, as the beam Y, W, X, Z.

If the surface M were so constructed that the beam should strike it at say $41\frac{1}{2}^\circ$, a large portion of the red rays would be reflected back along with the infra-red and thus a source (filament) giving out a light rich in red, could be made to give a pure white light. This also is of importance, as allowing incandescent lamps to be run "below voltage," this giving a very long life. While the lamp I have illustrated is an incandescent electric lamp, it is of course a simple matter to adapt the principle of the invention to any lamp using an incandescent body or bodies.

In regard to the modification shown in Fig. 2 one mode of forming the bulb is to make it in two concentric pieces, one fitting snugly over the other, as shown, the line of cleavage C intersecting the inclosed spaces and the prisms X and W being separately inserted before the two parts of the bulb are put together.

The word "regenerative" in this application and in the claims, is employed in the sense of "being used again or repeatedly without appreciable or apparent loss." The term "selective reflector" used in this application and in the claims, means any sort of a reflector or reflecting surface or object which has the capacity of separating the luminous radiation from the non-luminous, allowing one class of radiation to radiate and reflecting the radiation of the other class to a source of radiation.

Having thus described my invention, what I claim and desire to secure by Letters Patent is—

1. A method of producing light from an incandescent source, which consists in separating the luminous radiation from the infra-red radiation, allowing the luminous radiation to radiate freely and directing the infra-red radiation back to the source.

2. A method of producing light from an incandescent body or source, which consists in separating the luminous waves from the

non-luminous, allowing the luminous waves to radiate freely and using the non-luminous waves regeneratively.

3. A method of producing light from an incandescent source, which consists in selecting the luminous radiation and directing the non-luminous radiation back to the incandescent source.

4. A method of producing light from an incandescent source, which consists in selecting the luminous radiation, directing the non-luminous radiation back to the incandescent source, and allowing the luminous to radiate freely.

15 5. The method of producing light, which consists in separating part of the luminous radiation from an incandescent source and reflecting the non-luminous radiation together with a certain amount of red rays 20 back to the incandescent source and transmuting the same to produce a white light.

6. The method of producing radiation of desired wave length from a source emitting waves of various lengths, which consists in 25 selecting the desired radiation and directing the remainder of the radiation back to the source and using it regeneratively.

7. The method of producing radiation of desired wave length from a source emitting 30 waves of various wave lengths, which consists in the use of a selective reflector which selects radiation of the desired wave length and directs the radiation of other wave lengths back to the source.

35 8. A method of producing radiation from an incandescent source, which consists in separating the radiation of luminous character from the radiation of non-luminous character, allowing the radiation of one 40 character to radiate freely, and directing the radiation of the other character back to the source.

9. The method of producing luminous radiation from an incandescent source, 45 which consists in allowing the luminous radiation to radiate freely and concentrating and converting the non-luminous radiation into luminous radiation by raising the temperature of a radiant body, said converted radiation being allowed to radiate freely.

50 10. A method of producing radiation from an incandescent source, which consists in separating the radiation of luminous char-

acter from the radiation of non-luminous character, allowing the radiation of one character to radiate freely, and using the radiation of the other character regeneratively.

11. The method of producing luminous 60 radiation from an incandescent source, which consists in allowing the luminous radiation to radiate freely for illuminating purposes and converting the non-luminous radiation into luminous radiation through 65 the medium of a selective reflector and an incandescent source, said converted radiation being allowed to radiate freely.

12. The method of producing luminous radiation from an incandescent source, which 70 consists in separating the luminous radiation from the non-luminous radiation, allowing the luminous radiation to radiate freely and in concentrating and converting the non-luminous radiation into luminous radia- 75 tion by raising the temperature of a radiant body, said converted radiation being allowed to radiate freely.

13. The method of producing luminous radiation from an incandescent source, 80 which consists in separating the luminous radiation from the non-luminous radiation by selective reflection, allowing the luminous radiation to radiate freely and returning the non-luminous rays to the initial incandescent source, thereby converting the non-luminous radiation into luminous radiation, 85 said converted radiation being allowed to radiate freely.

14. The method of producing radiation of 90 desired wave length from an incandescent source emitting waves of various lengths, which consists in allowing the radiation of desired wave length to radiate freely and in concentrating and converting the radiation 95 of other wave lengths into radiation of desired wave length by their action on the temperature of a radiant body, which converted radiation is then allowed to radiate
